ELECTRICAL CONNECTION APPARATUS

Harry A. Douglas, Bronson, Mich., assignor to
 Kingston Products Corporation, a corporation
 of Indiana

Application May 31, 1935, Serial No. 24,255

9 Claims. (Cl. 173—328)

My invention relates to electrical connection apparatus, such as switches, sockets, and the like, and more particularly to electrical connection means which may be combined with and embodied in various forms of electrical connection apparatus. In the present embodiment of my invention the electrical connection means comprises a terminal post adapted for the reception of a plug conductor terminal of the snap type, and by embodiment of such an electrical connection means in electrical connection apparatus of various forms, the apparatus is adapted for use with plug conductor terminals of the snap type. The principal object of my invention is to provide new and improved electrical connection apparatus and means of the foregoing types. In the drawing accompanying this specification and forming a part of this application, I have shown for purposes of illustration, one form which my invention may assume, and in this drawing:

Figure 1 is a plan view of an electrical switch embodying my invention, the switch being fragmentarily shown.

Figure 2 is a perspective view of one of the terminal posts of the switch shown in Figure 1, the switch base and the casing being shown fragmentarily.

Figure 3 is a longitudinal section of a terminal post taken along the line 3—3 of Figure 1, the base being fragmentarily shown and the casing with the switch omitted.

Figure 4 is a section taken on the line 4—4 of Figure 3.

Figure 5 is a horizontal section taken on the line 5—5 of Figure 3, and

Figure 6 is a horizontal section taken on the line 6—6 of Figure 3.

Referring to Figure 1 of the drawing the switch here shown includes an insulating base 11 closing the top of a casing 12, the casing 12 being provided with fingers 13, the tips 14 of which are clinched over the top of the insulating base 11. The casing 12 is provided with a bracket 15, fragmentarily shown, whereby the casing 12 may be suitably mounted. Within the switch casing 12 is disposed a movable switch member (not shown) operable by means of a reciprocable actuator 16 fragmentarily shown. The movable switch member is cooperable with contact studs, one of which 17 is shown in side elevation in Figure 3. Each contact stud, in this instance, is provided with a contact head 18 and has a shank 19 disposed through the insulating base 11. The contact head 18 may be seated in a recess 20 in the inside face of the base 11, and

may project somewhat from the inside face of the base 11. The end 21 of the shank may be spread laterally, as by riveting, swedging, or spinning, either over the upper surface of the insulating base or over a conductor which it is desired to electrically connect to the contact stud 17.

In this instance certain of the contact studs are electrically connected to and hold in position on the base 11 a plurality of terminal posts, 22 through 28, the number of posts depending on the nature of the switch and the desired circuit connections.

The terminal posts, 22 through 28, in the present embodiment are all identical, and a description of the construction of one of them will serve for all.

Referring more particularly to the terminal post 22 shown in Figures 2 through 5, this post comprises a tubular body portion 29 of generally 20 oblong rectangular cross-section, having narrower opposite walls 30, 31, and wider opposite walls 33, 34 at right angles to the narrower walls 30, 31. The wider wall 33 is made in halves, one half 35 being integral with the narrower wall 30 and the other half 36 being integral with the narrower wall 31. The wall halves 35, 36 have their adjacent edges in abutment along a longitudinal line or plane of abutment 65. The other wider wall 34 is also made in halves, one half 37 being integral with the narrower wall 30 and the other half 38 being integral with the narrower wall 31. The wall halves 37, 38 have their adjacent edges in abutment along a longitudinal line or plane of abutment 66. The narrower walls 30, 31 are integrally joined at their tops by a loop 39 providing an aperture 40. The legs of the loop 39 are shown as having margins 70, 71 tapering from the bight of the loop to the junction between the legs of the loop and the top of the walls 30, 31. The upper ends of the wider walls 33, 34 may have arcuate margins 41, 42 conforming generally to the aperture 40 formed by the loop 39.

The narrower wall 30 has its lower end extended and bent outwardly at right angles from that wall to form a foot 43. The wall halves 35, 37, formed integrally with the narrow wall 30, also have their lower ends extended and bent outwardly at right angles from the wall halves 35, 37 to form oppositely extending feet 44, 45. The lower end of the other narrower wall 31 is extended and bent outwardly at right angles thereto to form a lateral extension 46 which, in this instance, is wider than the narrower wall 35.

31. The under surface of the lateral extension 46 is in a plane common with the bottoms of the feet 43, 44, 45. In this instance the lateral extension 46 is integral with a further extension, 5 serving as a base plate 47, underlying the lateral extension 46 and the feet 43, 44, 45. The base plate 47 is integrally joined to the lateral extension 46 at a fold 48. The base plate 47 is thus an integral part of the terminal post 22 as a 10 whole. The base plate 47 is desirably long enough so as to provide a portion 49 at its free end which may be folded around the end of the foot 43 extending from the narrower wall 30, and over and against the top of that foot. The folded 15 overlying portion 49, being wider than the foot 43, may have its lateral marginal portions 50, 51 pressed down against the upper surface of the base plate 47 of the terminal post, so as to form a pocket in which the foot 43 is tightly held 20 not only against vertical movement but also against lateral movement.

The distance between the ends of the feet 44, 45 is desirably the same or less than the width of the base plate 47.

25. Detent means 52 is provided for cooperation with the aperture 40 formed by the loop 39, and with a plug conductor terminal insertable in the aperture 40. In this instance the detent means 52 is generally of U-shape having a plane bight 30 53 from which extend legs 54, 55. The detent means 52 also includes a protuberance 56 of generally semi-cylindrical form, desirably struck up from the bight 53 of the U, the axis of the semi-cylindrical protuberance 56 being disposed at 35 right angles to the axis of the aperture 40 formed by the loop 39. The detent means 52 is slidable within the body portion 29 of the terminal post, upward movement of the detent means 52 being limited by engagement of opposite margins of the bight 53 of the detent means 52 with shoulders 57, 58 formed by inward extensions on the narrower walls 30, 31 at approximately the tops of these walls, where these walls join the ends of the loop 39.

40. The detent means 52 is biased toward the aperture 40 formed by the loop 39 by means of a helical spring 59, one end of which engages the underside of the bight 53 of the detent means 52 and the other end of which engages the base plate 47 of the terminal post.

45. The lateral extension 46 of the terminal post is provided with an aperture 60, through which may be passed the shank of a rivet or the shank 19 of a switch contact stud 17. The base plate 55 47 of the terminal post is provided with an aperture 61 concentric with the aperture 60 in the lateral extension 46. The aperture 61 in the base plate 47 is desirably somewhat larger than that in the lateral extension, so that when, as in the 60 present embodiment, the base plate is made by folding a long lateral extension of a wall of the body of the terminal post, allowance will be made for any lack of registry between the centers of the apertures 60, 61 in the lateral extension 46 and in the base plate 47.

65. The terminal post 22 is desirably provided with means for preventing turning of the post about the shank 19 of the switch contact stud 17. In this instance the base plate 47 has struck downwardly therefrom, from the margin of the aperture 61, a projection 62 extending at right angles to the base plate and adapted to fit in a slot or recess 63 extending radially from an aperture 64 in the base 11. The shank 19 of the contact stud 70 75 is adapted to pass through the base aperture 64,

through the apertures 61, 60, and have its end 21 overlie the lateral extension 46, to hold the terminal post to the base 11.

It will be evident that by mounting the terminal posts 22 through 28 (where a plurality of posts are used) at an appropriate angle with respect to each other, the longitudinal axis of the apertures 40 formed by the loops 39 of the terminal posts may be so directed that plug conductor terminals may be readily inserted in these apertures without interfering with each other in inserting and removing them.

The plug conductor terminals are of the usual snap type comprising a generally cylindrical portion 73 and an annular furrow 72 in the cylindrical portion, the terminal being provided with a frusto-conical end 67. The plug terminal is desirably swaged to the conductor disposed therein, as indicated by the swedge indentations 68. When the plug terminal is inserted in the loop 20 aperture 40, the frusto-conical end 67 serves to cam the detent means 52 downwardly against the bias of the spring 59, further inserting movement causing the protuberance 56 of the detent means to snap into the annular furrow 72 in the 25 plug terminal.

It will be evident that a terminal post such as 22 may have its body 29, the loop 39, the lateral extension 46, the feet 43, 44, 45, and the plate 47 made from a single integral sheet metal stamping, bent to the form hereinbefore described. The detent means 52 may also be formed from sheet metal.

Considerable push or pull is required to insert into or remove from a terminal post a plug conductor terminal of the snap type, as hereinbefore described. It will be apparent that the construction of the terminal post is designed to resist bending stresses, caused by such a push or pull, or otherwise tending to bend the body portion of the terminal post with respect to the compound supporting extension.

From the foregoing it will be apparent to those skilled in the art that the illustrated embodiment of my invention provides new and improved electrical connection means and apparatus, readily and conveniently constructed and assembled, and accordingly, accomplishes at least the principal object of my invention. On the other hand, it also will be obvious to those skilled in the art that the illustrated embodiment of my invention may be variously changed and modified, or features thereof, singly or collectively, embodied in other combinations than those illustrated, without departing from the spirit of my invention, or sacrificing all of the advantages thereof, and that accordingly, the disclosure herein is illustrative only, and my invention is not limited thereto.

I claim:

1. Conductor terminal receiving means, comprising: a body portion made of a single piece of sheet metal, said body portion having walls forming a tubular formation, and certain of said walls providing an aperture, one of the walls of said body portion being formed with a projection, 60 and another of said walls being formed with an extension, said extension being folded upon itself, and the folded portion thereof being extended and engageable with said projection; and detent means cooperable with said aperture and with a conductor terminal receivable in said aperture.

2. Conductor terminal receiving means, comprising: a body, formed of a single piece of sheet-metal, and having a tubular portion formed with 70 75

an integral loop at one end, and integral laterally extending parts adjacent the other end; one of said laterally extending parts being folded upon itself, and the extremity of the folded part being constructed and arranged to interlock with the other of said laterally extending parts.

3. Conductor terminal receiving means, comprising: a body, formed of a single piece of sheet-metal, and having a tubular portion, formed with an integral loop at one end for receiving a conductor terminal; biasing means disposed within said tubular portion, and constructed and arranged to yieldably engage a conductor terminal disposed in said loop; said body having integral laterally extending parts adjacent the other end, one of said parts being folded upon itself to provide a reversely extending portion spanning said other end of said tubular portion, and holding said biasing means in operative relation within said tubular portion, and the extremity of said reversely extending portion being constructed and arranged to interlock with the other of said parts.

4. Conductor terminal receiving means, comprising: a body, formed of a single piece of sheet-metal, and having a tubular portion, formed with an integral loop at one end, and integral laterally extending parts adjacent the other end; one of said parts being folded upon itself to provide a reversely extending portion spanning the other end of said tubular portion, the extremity of said reversely extending portion being constructed and arranged to interlock with the other of said parts; and feet, integrally formed with said tubular portion, and bearing on said reversely extending portion.

5. Conductor terminal receiving means, comprising: a body, formed of a single piece of sheet-metal bent to provide a tubular portion and a loop portion at one end of said tubular portion, and bent also to provide a laterally extending part folded upon itself to span the other end of said tubular portion, the extremity of said laterally extending part being connected to said body.

6. Conductor terminal receiving means, comprising: a sheet-metal body, of polygonal cross-section, opposite walls adjacent the upper end of said body being extended and joined to form a loop for receiving a conductor terminal, one of said opposite walls at the lower end of said body being laterally extended away from said body and being folded upon itself to underlie and close off the lower end of said body, the extremity of said

extension being secured to the other of said opposite walls.

7. Conductor terminal receiving means, comprising: a sheet-metal body, having an aperture for receiving a conductor terminal, one wall portion of said body adjacent one end being laterally extended away from said body, and the opposite wall portion at said one end being laterally extended away from said body, this lateral extension being widened and folded upon itself to underlie said one end, and having its extremity crimped over the defining marginal surfaces of the lateral extension of said one wall portion.

8. Conductor terminal receiving means, comprising: a sheet-metal body of polygonal cross-section, certain of the walls adjacent the upper end of said body being apertured for receiving a conductor terminal, opposite walls at the lower end of said body being laterally extended away from said body, one of these lateral extensions being wider than the wall it is extended from, and folded upon itself to underlie and close off the lower end of said body, the extremity of the widened lateral extension being crimped over the defining marginal surfaces of the other lateral extension, and other opposite walls at the lower end of said body having laterally extending feet resting on the underlying part of said widened lateral extension.

9. Conductor terminal receiving means, comprising: a sheet-metal body of polygonal cross-section, opposite walls adjacent the upper end of said body being extended and joined to form a loop for receiving a conductor terminal, said opposite walls at the lower end of said body being laterally extended away from said body, one of these lateral extensions being wider than the wall it is extended from, and folded upon itself to underlie and close off the lower end of said body, the extremity of the widened lateral extension being crimped over the defining marginal surfaces of the other lateral extension, and other opposite walls at the lower end of said body having laterally extending feet resting on the underlying part of said widened lateral extension; and biasing means, disposed within said body, having one end bearing on the overlying part of said wider lateral extension, and its other end in position to yieldably engage a conductor terminal disposed in said loop.

HARRY A. DOUGLAS. 50
